FURNITURE SEAT

Luther D. Lichty, Reading, Pa., assignor to
 Duplex Swing-Spring Seat Company, Inc.,
 Reading, Pa., a corporation of Pennsylvania

Application May 13, 1930. Serial No. 451,912

8 Claims. (Cl. 155—179)

My invention relates to furniture seats, and more particularly to the spring structure of such seats.

Heretofore, in the production of upholstered furniture, the general practice has been to support the upholstery springs by means of webbing secured to the under side of the frame of the article of furniture. In some instances, ordinary wooden slats have been used in lieu of fabric webbing, but the use of such slats has not proven satisfactory because of the tendency of the load upon the seats to loosen the nails securing the slats in position.

While the use of webbing has been and still is very extensive, such webbing has a tendency to stretch and also to tear loose from the securing tacks, thus permitting the sagging of the seat in its entirety.

It has been proposed to substitute for the webbing or slats supporting the upholstery springs, a structure consisting of a fabric sheet or fabricated wire frame resiliently supported by means of springs under tension connected about the edges thereof and secured to the bars of the frame, the construction being similar to that used in some forms of bed springs.

With the above conditions in mind, I have provided a furniture seat wherein the upholstery springs are supported from a rigid member which is suspended from the frame of the seat of the article of furniture solely by means of vertically extending expansion springs, thus permitting not only a directly vertical play of the upholstery springs support, but a swaying of said support, which will add materially to the comfort afforded by the seat of the article of furniture.

The tension of the expansion springs is relatively greater than the normal tension of the compressive upholstery springs, but relatively lower than the increased tension of said springs, developed by their compression, actual practice having demonstrated that notwithstanding the overloading of the upholstery springs, it is impossible to compress them to an extent to cause their complete collapse upon the slats supported by the suspension springs.

In order to permit the economical assembly of the seat spring structure in the article of furniture, and also secure the desired freedom of movement of the slats suspended by expansion springs from the frame of the seat, I provide special fittings which may be conveniently attached to the lower bars of the main seat frame; are so supported by said bars as to minimize, if not actually prevent, possibility of the loosen-

ing of the fitting as a result of loads applied thereto through the slats and the suspension spring structure supporting same, and so position the expansion suspension springs as to afford clearance about same to permit of the swaying of the whole spring structure.

The construction of these fittings is also such as to permit the rapid and convenient locating of the various members of the spring rigging upon the seat frame and in relation to the bars to which they are secured, and to facilitate the mounting of the slats and the suspension springs in the structure of the article of furniture.

The invention consists primarily in a furniture seat embodying therein a seat frame, a rigid upholstery spring supporting member, compressible upholstery springs secured thereto, vertically extending expansion springs, means attaching the top of said vertically extending expansion springs to the seat frame, and means attaching the bottom of said vertically extending expansion springs to said rigid member, said vertically extending expansion springs being spaced within the seat frame to permit the free movement of said rigid member; and in such other novel features of construction and combination of parts as are hereinafter set forth and described, and more particularly pointed out in the claims hereto appended.

Referring to the drawing,

Fig. 1 is a view of a settee or sofa, partly broken away to disclose a seat construction embodying the invention;

Fig. 2 is an enlarged, laterally condensed view on the line 2—2 of Fig. 1;

Fig. 3 is a section on the line 3—3 of Fig. 2 upon a still larger scale;

Fig. 4 is a view from the right of Fig. 3; and

Fig. 5 is a view of the application of the invention to a wooden plate instead of to slats as shown in the other figures.

Like numerals refer to like parts throughout the several views.

The embodiment of the invention shown in the drawing, is in connection with a settee or sofa indicated at 10. The seat portion of the sofa includes an upper bar or rail 11, and a lower bar or rail 12. The construction shown is that now commonly used, particularly with what is known as overstuffed furniture, using removable cushions shown at 13. These cushions ordinarily contain springs known as cushion springs which are not shown in the drawing as they have no bearing upon my invention.

Such cushions 13 are supported by the main

85

90

95

100

105

110

seat structure, which embodies therein a fabric top 14 secured to the top bar or rail 11 of the seat structure, compression upholstering springs 15 and a supporting structure secured to the bottom bar or rail 12 of the seat structure. This supporting structure as now extensively used, consists of webbing so interlaced and secured as to withstand the ordinary wear and tear to which the articles of furniture are subjected. As above stated, it has sometimes been the practice to firmly support wood slats from the lower rail structure 12 as an upholstering spring support in lieu of the burlap webbing generally used.

In the seat of my invention, I provide a rigid upholstering spring supporting member consisting of either a thick wood slat 16 or a thick wood panel 17 as shown in Fig. 5. The springs 15 may be connected to said slats by means of staples or in any other desired manner, and to the top facing 14 by being sewed thereto in the usual manner.

The slats 16 or the panel 17 is suspended from the lower bar or rail 12 by means of vertically extended extension springs 18, the tension of which is relatively greater than the normal tension of the compression upholstering springs 15. I prefer to use slats, as 16, since this permits a larger measure of resiliency in the seat as a whole. With a chair or sofa of average size, I prefer to use two springs 18 at each end of each slat although with smaller chairs or sofas, only one spring need be used and with larger chairs or sofas, three springs may be used. The strength of the springs is determined entirely by the character of the chair or sofa and the degree of resiliency required by the manufacturer.

The springs 18 are supported from the front and rear bars or rails 12 by means of a metallic fitting 19 having a face flange 20 adapted to fit snugly against the bar or rail 12, this flange being of a depth to resist toppling of the fitting. Extending from the fitting 19 inwardly of the bar or rail 12, is an angular section 21 having a depending front flange 22 provided with openings as 23 to receive the hooked upper end or top 24 of the spring 18. The number of openings 23 is determined by the number of springs it is desired to use or to permit variation in the number of springs.

The fitting 19 also has a second angular section 25, extending over the top of the bar or rail 12 and having a depending tongue 26 adapted to fit in a groove or mortise 27 formed in the top of the bar or rail 12. The fitting 19 may be secured snugly against the bar or rail by means of a nail or screw as 28 passing through face flange 20.

The use of a tongue and groove or mortise 27 permits the convenient locating of the fitting 19, and since the bar or rail 12 is ordinarily made of hard wood, will also aid in preventing the toppling of the fitting from loads applied to the springs 18 which are spaced away from the bar or rail 12.

The lower end or bottom of the spring 18 is connected with the slat 16 by means of a channel fitting 29, having a lower horizontal side flange 30 upon which the slat is adapted to rest and an upper horizontal side flange 31 adapted to engage the top of the slat as shown more particularly in Figs. 3 and 4. The bottom of the channel fitting 29 extends vertically and abuts against the end of the slat and may be secured firmly in this position in any desired manner as by means of a screw or nail 32. In order to minimize likelihood

of escape of the fitting from the end of the slat, I provide the lower side flange 30 with an upwardly extending tongue 33 adapted to enter a groove or mortise 34 in the bottom of the slat. The bottom of the fitting 29 is provided with an upwardly extending flange 35 having openings therein adapted to receive the bent lower end 36 of the springs 18. Fittings 19 are located opposite each other upon the front and back bars or rails 12 of the lower frame of the seat and both ends of the slat 16 are equipped with fittings 29. The slats are thus resiliently supported at each end by means of suspension springs which permit a limited swaying action of the slat as a whole as well as the lowering of the slat against the tension of the springs 18.

The operation of the herein described is substantially as follows:

The manner of assembling the seat structure of the invention depends entirely upon the system prevailing in a factory. If desired, the fittings 19 may be mounted upon and attached to the bars or rails 12 without having the springs 18 attached thereto, and the fittings 29 may be attached in like manner to the slats 16 or plate 17. The upholstery springs 15 may then be mounted upon the slats 16 or plate 17.

The nails or screws 28 and 32 are used mainly to prevent displacement of the fittings 19 longitudinally of the bars, or the escape of the slats 16 from the channelled end fittings 29. These nails or screws, however, have the further function of relieving the woodwork to which the fittings are secured from unnecessary strains which might lead to the splitting thereof.

The grooves or mortises 27 and 34, in their co-operation with the tongues or flanges 26 and 33, serve to prevent play between the fittings and the bars 12 and the slats 16 respectively. They have little or no effect in preventing toppling of the fittings in relation to the bars 12 or the slats 16, since the vertically extending flange 20 and the top flange 25 of the fitting 19, and the bottom of the channel 29, and the side flanges 30 and 31, present angularly disposed surfaces of large area engaging the bars or rails 12 and inclosing the ends of the slats 16 which check any tendency of the fittings to topple. The tongues 26 and 33, however, are a safeguard supplementing the action of the nails or screws 28 and 32 in maintaining the fittings in their established position in relation to the bar or rail 12 and the slats 16 or plate 17.

When the fittings have been properly connected, the fittings 19 to the front and back bars or rails 12, and the fittings 29 to the slats 16 or plate 17, the slats may be assembled in the seat structure by merely hooking the ends 22 of the springs co-operating with each fitting in the openings 23 of the fitting 19, and the ends 36 in the openings in the upwardly extending flange 35 of the fitting 29. The cloth 14 may then be attached to the springs 15 and to the upper bars or rails 11 of the frame in the usual manner.

With the parts so assembled, the entire seat structure is suspended from the bars or rails 12 by the springs 18, and the springs 15 are held under tension between the cloth 14 and the slats 16 in the usual manner, the normal tension of such springs 15 being lower than that of the springs 18.

Any desired number of slats may be used, varying with the size of the article of furniture. In a settee or sofa the distribution and number of

slats will be determined by the number of cushionings. If a plate 17 be used, there will be one plate to each cushion.

It will be noted that the springs 18 are spaced well away from the front and back bars or rails 12, and that the slats in their entirety are located between such springs. Consequently, the slats in their entirety may sway in any direction in a horizontal plane, as well as have vertical movement against the tension of the springs 18.

If three or more slats are used in a chair it is obvious that the springs 18 by means of which each slat is suspended, may expand to a variable extent, according to the point of application of the load to the seat, but that the sagging of the seat is prevented, even after long continued use, because immediately upon the springs 15 and 18 being relieved from a load their reflex action will restore all of the parts to their normal positions.

Experience has shown that, aside from permitting a swaying action, the springs 18 sustain the load applied to the springs 15 unless these springs are subjected to an abnormally heavy load. The springs 18, however, will always have a cushioning action and will always permit the slight swaying action above referred to.

If, however, the springs 15 are subjected to an excessive load, the tension developed therein as a result of the collapsing of the springs under this load will exceed the normal tension of the springs 18 and thus divide the cushioning effect between the springs 15 and the springs 18, and avoid that jar which would result from the total collapsing of the springs 15.

By an arrangement of upholstery springs 15 and suspension springs 18, coacting in the manner described, overloading of the former is prevented and likelihood of weakening or breakage of such springs, as a result of such overloading, is eliminated.

Ordinarily two springs 18 are used with each pair of fittings 19 and 29, and this is desirable as tending to avoid any tilting of the slats 16. If a plate 17 be used, however, only one spring may be used with each fitting, although I prefer to use at least two springs.

The springs 18 always hang vertically from the fittings 19. This ensures the highest cushioning effect and avoids a sagging effect in the seat. In other words, the entire seat when subjected to a load has a tendency to descend vertically, thus effectively distributing the load throughout all of the upholstery springs 15 and suspension springs 18 affected by the load, and the rebound of the springs is also vertical thus tending to remove all likelihood of sagging of the seat, since even if the various springs should weaken, the only effect would be a lowering of the seat in its entirety.

The desirability of a seat embodying the invention resides more particularly in its great resiliency, great comfort and great durability. In cost there is no substantial saving over present methods of forming the seat.

It is not my intention to limit the invention to the precise details of construction shown in the accompanying drawing, it being apparent that such may be varied without departing from the spirit and scope of the invention.

I believe it to be broadly new, however, to provide in a furniture seat a rigid supporting member for the upholstery springs which is suspended from the seat frame by means of vertically ex-

tending expansion springs, so as to afford what may be termed a full floating spring seat rigging as distinguished from a construction in which the supports for the upholstery springs are rigidly connected with the seat frame.

80

Having described the invention, what I claim as new and desire to have protected by Letters Patent, is:—

1. A furniture seat embodying therein a seat frame having front and rear bars, a rigid upholstery spring supporting member, compressible upholstery springs secured thereto, vertically extending expansion springs, metal fittings secured to the front and rear bars of the seat frame, each having a face flange adapted to abut against said bar, an angular section, having a depending front flange provided with openings therein by means of which said expansion springs may be attached thereto, projecting from the top of said face plate inwardly of the frame, and a second section projecting from the top of said face plate extending over and in engaging relation with the top of the bar of the frame, and means holding said face flange in said abutting relation to said bars, and means attaching the bottom of said expansion springs to said rigid member, said expansion springs being spaced within the seat frame to permit the free movement of said rigid member.

85

2. A furniture seat embodying therein a seat frame having front and rear bars, a rigid upholstery spring supporting member, compressible upholstery springs secured thereto, vertically extending expansion springs, metal fittings secured to the front and rear bars of the seat frame, each

90

having a face flange adapted to abut against said bar, an angular section, having a depending front flange provided with openings therein by means of which said expansion springs may be attached thereto, projecting from the top of said face plate inwardly of the frame, and a second section projecting from the top of said face plate extending over and in engaging relation with the top of the bar of the frame, and means holding said face flange in said abutting relation to said bars, and means attaching the bottom of said expansion springs to said rigid member, said expansion springs being spaced within the seat frame to permit the free movement of said rigid member.

95

3. A furniture seat embodying therein a seat frame having front and rear bars, a rigid upholstery spring supporting member, compressible upholstery springs secured thereto, vertically extending expansion springs, metal fittings secured to the front and rear bars of the seat frame, each

100

having a face flange adapted to abut against said bar, an angular section, having a depending front flange provided with openings therein by means of which said expansion springs may be attached thereto, projecting from the top of said face plate inwardly of the frame, and a second section extending over the top of the bar having a downwardly extending tongue, said bars being mortised along the top to receive said last

105

named depending tongues, and means holding said face flange in said abutting relation to said bars, and means attaching the bottom of said expansion springs to said rigid member, said expansion springs being spaced within the seat frame to permit the free movement of said rigid member.

110

4. A furniture seat embodying therein a seat frame, a rigid upholstery spring supporting member, compressible upholstery springs secured thereto, vertically extending expansion springs, means attaching the top of said springs to the seat frame, and channelled fittings embracing opposite edges of said supporting member, with the bottom of the channel of the fitting in abutting relation to the edge embraced thereby, means

115

maintaining said flange with the bottom of said fitting in such abutting relation, and means whereby the bottom of said expansion springs may be attached to said channelled fittings.

120

5. A furniture seat embodying therein a seat frame, a rigid upholstery spring supporting member, compressible upholstery springs secured thereto, vertically extending expansion springs, means attaching the top of said springs to the seat frame, and channelled fittings, side flanges upon said fittings, said side flanges embracing the end and engaging the opposite faces of said

125

supporting member, with the bottom of the fitting in abutting relation to the edge embraced thereby, means maintaining said flanges in relation to said supporting member, and an upward-

130

6. A furniture seat embodying therein a seat frame, a rigid upholstery spring supporting member, compressible upholstery springs secured thereto, vertically extending expansion springs, means attaching the top of said springs to the seat frame, and channelled fittings, side flanges upon said fittings, said side flanges embracing the end and engaging the opposite faces of said

135

supporting member, with the bottom of the fitting in abutting relation to the edge embraced thereby, means maintaining said flanges in relation to said supporting member, and an upward-

140

7. A furniture seat embodying therein a seat frame, a rigid upholstery spring supporting member, compressible upholstery springs secured thereto, vertically extending expansion springs, means attaching the top of said springs to the seat frame, and channelled fittings, side flanges upon said fittings, said side flanges embracing the end and engaging the opposite faces of said

145

supporting member, with the bottom of the fitting in abutting relation to the edge embraced thereby, means maintaining said flanges in relation to said supporting member, and an upward-

150

- ly extending flange having openings therein to receive the lower ends of said expansion springs.
5. A furniture seat embodying therein a seat frame, a rigid upholstery spring supporting member, compressible upholstery springs secured thereto, vertically extending expansion springs, means attaching the top of said springs to the seat frame, and channelled fittings, side flanges upon said fittings, said side flanges embracing the end and engaging the opposite faces of said supporting member, with the bottom of the fitting in abutting relation to the edge embraced thereby, the side flange engaging the bottom of said member having an upwardly directed tongue, said member being mortised adjacent each edge thereof to receive the tongue of the fitting embracing said edge, and an upwardly extending flange having openings therein to receive the lower ends of said expansion springs.
- 10 6. A furniture seat embodying therein a seat frame having front and rear bars, a rigid upholstery spring supporting member, compressible upholstery springs secured thereto, vertically extending expansion springs, metal fittings secured to the front and rear bars of the seat frame, each having a face flange adapted to abut against said bar, a section projecting inwardly of the frame from which said expansion springs are suspended, and means holding said face flange in said abutting relation to said bars, and channelled fittings, side flanges upon said fittings, said fittings embracing the end and engaging the opposite faces of said supporting member, with the bottom of the channel of said fitting in abutting relation to said edge, means maintaining the edge of said supporting member and the bottom of the channel of said fitting in such abutting relation, and means whereby the bottom of said expansion springs may be attached to said channelled fittings.
- 15 7. A furniture seat embodying therein a seat frame having front and rear bars, a rigid upholstery spring supporting member, compressible upholstery springs secured thereto, vertically extending expansion springs, metal fittings secured to the front and rear bars of the seat frame, each having a face flange adapted to abut against
- 100 said bar, an angular section, having a depending front flange provided with openings therein by means of which said springs may be attached thereto, projecting from the top of said face plate inwardly of the frame, and a second angular section extending over the top of the bar having a downwardly extending tongue, said bars being mortised along the top to receive said last named depending tongues, and means holding said face flange in said abutting relation to said bars, and channelled fittings, side flanges upon said fittings, said side flanges embracing the end and engaging the opposite faces of said supporting member, with the bottom of said fitting in abutting relation to said edge, the side flanges engaging the bottom of said member having an upwardly directed tongue, said member being mortised adjacent opposite edges thereof to receive said tongues, and an upwardly extending flange having openings therein to receive the lower ends of said expansion springs.
- 105 8. A furniture seat embodying therein a seat frame having front and rear bars, a plurality of rigid wooden slats, compressible upholstery springs secured thereto, vertically extending expansion springs, metal fittings secured to the front and rear bars of the seat frame, each having a face flange adapted to abut against said bar, an angular section, having a depending front flange provided with openings therein by means of which said springs may be attached thereto, projecting from the top of said face plate inwardly of the frame, a second angular section extending over the top of the bar having a downwardly extending tongue, said bars being mortised along the top to receive said last named depending tongues, and channelled fittings, side flanges upon said fittings, said side flanges embracing the end and engaging the opposite faces of said slats respectively with the bottom of said fitting in abutting relation to said ends, the side flange engaging the bottom of said member having an upwardly directed tongue, said slats being mortised adjacent the opposite ends thereof to receive said tongues.
